(57) **CLAIM**

The ornamental design for an amusement ride, as shown and described.

DESCRIPTION

FIG. 1 is a right side perspective view of an embodiment of an amusement ride showing my new design, the left side of the amusement ride being a mirror image of the right side thereof;

FIG. 2 is a fragmented perspective view of FIG. 1 with the identical amusement ride being omitted for ease of illustration only;

FIG. 3 is a front view of FIG. 2;

FIG. 4 is a rear view of FIG. 2;

FIG. 5 is a left side perspective of a second embodiment of the amusement ride as disclosed in FIG. 1; the right side of the amusement ride being a mirror image of the left side thereof;

FIG. 6 is a fragmented perspective view of FIG. 5 with the identical amusement ride being omitted for ease of illustration only;

FIG. 7 is a front view of FIG. 5; and,

FIG. 8 is a rear view of FIG. 5.

The broken line showing is for illustrative purposes only and forms no part of the claimed design.
